UNITED STATES PATENT OFFICE.

HENRY S. CATE, OF MILLERSTOWN, (BARNHART'S MILLS P. O.,) PA.

IMPROVEMENT IN CHAIR SEATS AND BACKS.

Specification forming part of Letters Patent No. **204,480**, dated June 4, 1878; application filed February 19, 1878.

To all whom it may concern:

Be it known that I, H. S. CATE, of Millers-
town, Butler county, Pennsylvania, have in-
vented an Improvement in the Seats and Backs
of Chairs, of which the following is a specifi-
cation:

Figure 1 of drawing is a front elevation,
partly in section; Fig. 2, a top view, partly in
section; Fig. 3, a detail section of back.

The invention will first be described in
connection with the drawing, and then pointed
out in the claim.

In the drawing, A represents the frame of
chair; B, the seat or back, formed of any suit-
able material; and D, an intervening strip of
rubber or other elastic substance. The latter

is continuous, and gives a degree of spring
that furnishes a comfortable yielding support
to the body, is more economical than springs
or stuffing as usually employed, and is withal
of sufficient strength to be very durable.

Having thus described all that is necessary
to a full understanding of the invention, what
I claim as new and of my invention is—

The combination, with frame A and seat or
back B, of the intervening continuous elastic
strip D, as and for the purpose specified.

HENRY S. CATE.
